ROOFING

Ralph P. Muller, St. George, Staten Island, N. Y.,
assignor to Seal-Kast Corporation, a corpora-
tion of Delaware

Application January 27, 1930, Serial No. 423,885

6 Claims. (Cl. 108—6)

This invention relates to the art of roofing and to the protection or insulation of such surfaces and contemplates a novel method of applying waterproofing materials, insulation, and ornamentation to all kinds of roofing structures. An object of the invention is to provide an economical method of waterproofing and insulating roof structures, which is simple of operation and which eliminates, to a great extent, the expense of handling quantities of roofing units and other materials and the expense of transporting the same, not only to the point of destination, but from the ground to the roof.

Another object is to provide a satisfactory protection for roof structures which is not only absolutely waterproof but is also ornamental and which can be applied to any such roof surface in practically a single operation.

Another object is to provide a roofing material particularly adapted to be used in re-roofing jobs directly upon the old material of a roof structure over which it is impractical or impossible to lay any kind of known roofing products, such as tin or galvanized iron roofs.

Roofing material has heretofore been factory-made in various forms, and has required a great deal of handling and transporting before it is available at the job. Roofing material has also been applied on the job by various methods which include mopping the surface to be coated with liquid asphalt, laying impregnated and/or waterproofed paper thereover, and mopping the surface again and applying grit over the top to afford a wear-resisting and heat-resisting surface. The former procedure has necessitated considerable expenditures for transportation and handling before the product is available on the job and has also necessitated large labor costs on the job. The latter procedure has been found expensive because of the large amount of manual labor necessary to complete the various steps which must be carried out to obtain the completed water-proof application. An object of the invention is to eliminate or diminish the above-mentioned disadvantages and to produce a cheap and easily constructed water-proof roof structure, in which the application of the material is accomplished with great rapidity and with very little labor expense at the point of construction.

Other objects of this invention will hereinafter be set forth, or will be apparent from the description and the drawing, in which is illustrated one method of operation for carrying out the invention.

The invention, however, is not intended to be restricted to any particular application of such operation, or to any specific method of operation, or to any of various details thereof, herein shown and described, as the same may be modified in various particulars or be applied in many varied relations without departing from the spirit and scope of the claimed invention, the practical embodiments herein illustrated and described merely being descriptive of some of the various forms and modifications in which the invention might be embodied.

On the drawing, in which the same reference characters refer to the same parts throughout, and in which is disclosed such method of opera- 70

The figure is a perspective view, illustrating the manner of application of the invention to a roof construction, shown as under repair.

The invention consists essentially in forcing, by 75 compressed air or any fluid pressure, a continuous supply of waterproofing compound, in liquid state, up to and onto the roof surface to be coated, and, if desired, or if the character of the coating permits, simultaneously or immediately there- 80 after, forcing under similar pressure, a continuous supply of grit surfacing thereover and therein, thereby firmly imbedding, by such pressure, the grit into said waterproofing compound.

The process is applied particularly in connec- 85 tion with the application of waterproofing compound for roofing purposes, wherein, under pressure of the gaseous medium which is finally effective to drive the substances against the surface to be coated, or by means of some similar meth- 90 od of pumping or conveying the liquid or semi-liquid, and/or the granular, material from the source of supply to the roof or similar surface to be operated upon, the particular roofing com- 95 pound and/or the grit are brought in a continuous stream and continuously applied to the surface to be coated.

The pressure of the driving medium prefera- 100 bly is regulated so as to carry the base coating and/or waterproofing fluid, and if grit material is used, the grit material, forcibly onto the surface to be coated; because of the liquid, or semi- liquid application of the roof surface and the force of its application, all cracks, holes and interstices will be filled up and sealed by the wa- 105 terproofing compound. The grit can be applied in any desired manner, in plain, ornamental, or variegated designs and colors. The term, "grit", is used in this application for convenience in or- 110 der to refer to all kinds of material reduced to

small particle sizes which is adapted to serve as a surfacing or ornamenting medium for roofing, insulating, and covering materials. Preferably crushed slate is used because of its relatively low 5 price, availability and range of color, but it is understood that any material capable of reduction to relatively small sizes, such as glass shards, metal filings, sand, vitrified tile, porcelain, or other materials, may be used.

10 The application is accomplished by means of apparatus which will forcibly convey fluid waterproofing material and surfacing material from one position to another and then feed such materials to a nozzle or nozzles through which the 15 materials are delivered onto the roof surface to be protected. Preferably the waterproofing coating is applied slightly in advance of the grit so that the surface is thoroughly coated with the waterproofing material slightly prior to the time 20 when the grit is applied, thus ensuring a sticky or mastic layer on which and into which the grit may be embedded. The pressure of the waterproofing liquid is regulated as desired and should be strong enough to ensure penetration into all 25 available cracks, crevices, holes or graining in the covering surface, yet such pressure should not be so great as to cause the liquid to be splashed away from the immediate area of application. The invention is not to be limited to the use of 30 any particular coating material as any coating material, such as asphalt emulsified in liquids at ordinary temperatures, or materials which can be made liquid during application and which subsequently harden, dry or set into tough, flexible, solid or semi-solid waterproof bodies or films, 35 can be used.

I contemplate spraying metals in molten state on roofs which have or have not been treated with additional waterproofing coatings. In such 40 case, the molten metal is spread from an apparatus which melts a continuously fed strip or wire of metal and ejects molten fluid in a finely atomized spray. Preferably an old surface is first treated with bituminous material and grit 45 in order to preserve the same and to provide a strong key for subsequent applications of material, and also to provide a fire-proof base therefor, the molten metal being then applied. The bituminous material serves as waterproofing and 50 insulating material and is not subject to corrosion as by salt air or by the presence of gases in the air which ordinarily attack metal roofs. This material thus provides additional protection against weathering, should the outer metal film 55 be, by chance, perforated. In addition to the above mentioned advantages of the described construction, the uniform metallic film seals in the bituminous compound and the volatile oils thereof, so that no loss results in the waterproofing or 60 insulating qualities of the material.

By virtue of the forcible feeding alluded to, the water-proof coating is firmly adhered to the surface and forced into any holes, cracks or crevices which are present, thus ensuring that the 65 roof structure is thoroughly waterproof. If the cracks or holes are large, more than one application may be required, but under ordinary circumstances one coating is sufficient. The invention is well adapted for use on re-roofing jobs 70 where it is either undesirable, impossible or impracticable to apply known forms of roofing material owing to the characteristics of the material comprising the surface. The cracks and holes are completely filled with waterproofing 75 liquid which, after solidifying, renders the surface

impervious to the weather, and prevents loose or open edges or joints or flaps under which water or wind could ordinarily penetrate.

In applying color designs to the roof, the surfacing material, i. e., the grit, may be supplied 80 from a separate hopper or hoppers or other sources of supply. In such case, means are provided for controlling the color and/or quantity of grit supplied and/or the rate of mixing, so that the surfacing material may be applied to the 85 coated surface in any desired manner.

On the drawing, there is illustrated, in simple manner, a method of application of the invention, particularly to a roof construction 10, here shown as having a boundary wall 12. The roof surface 14 itself is shown as formed by boards 16, between which are left crevices 18. For illustrative purposes, at a chimney 20, a broken portion 22 is shown, such broken portion to be repaired, such repair being one of the possible features of construction work which may be carried out by application of the invention herein.

In making the roof construction, in accordance with this invention, material, such as an asphalt emulsion, is first sprayed upon the surface to 100 be protected. Preferably, following closely after the application of the emulsion, grit particles are sprayed upon the surface coated with the emulsion. If desired, a metallic spray may be co-ordinated with one or both of the other sprays, 105 as herein described.

On the drawing, nozzles 24 and 26 are intended to illustrate, respectively, a nozzle spraying the asphalt emulsion, and a nozzle spraying the grit particles. As shown, the emulsion has coated 110 over the roof surface defined by boards 16, and has even been extended to seal crevices 28 at the junction of roof surface 14 with boundary wall 12 and chimney 20. Coating 30, for this purpose, may be extended up the side of the 115 boundary wall a sufficient distance to assure a proper seal at this position.

Following immediately upon the deposit of coating 30, or at a sufficient interval that the coating will still be plastic and sufficiently fluid 120 in order to receive the sprayed particles, permit them to become imbedded to a slight degree in the coating, and become bonded to the coating, nozzle 26 is made effective. Grit particles 32 thus define their layer 34. As here shown, 125 the two spraying operations are carried on substantially simultaneously, so that a section 36 of coating 30 will be clear of particles for a predetermined interval to permit a degree of hardening of the coating before the particles 130 fall upon it.

When broken portion 22 will be reached—and such portion is generally nothing more than a frayed or worn section of the timbers or other defects in the materials,—the coating composition will be effective to fill up that broken portion completely, sealing it as it does crevices 135 18 and other similar defects in the ordinary roof surface.

Many other changes could be effected in the methods of operation set forth, and in specific details thereof, without substantially departing from the invention intended to be defined in the claims, the specific description herein being for embodiments capable of carrying out the spirit of the invention.

Having thus described my invention, I claim:

1. The construction of a moisture-impervious roof construction from a roof construction having inherent moisture-pervious characteristics, in

- which the moisture-pervious roof construction has been located and assembled in position for use as such, which includes the steps of: forcing, under pressure, a continuous stream of liquid water-proofing compound to and spraying the compound onto the surface of the moisture-pervious roof construction to form a substantially unitary coating for the roof construction; and then spraying a continuous stream of protective material onto the coating. 50
2. The construction of a moisture-impervious roof construction from a roof construction having inherent moisture-pervious characteristics in which the moisture-pervious roof construction has been located and assembled in position for use as such, which includes the steps of: forcing, under pressure, a continuous stream of liquid water-proofing compound to and spraying the compound onto the surface of the moisture-pervious roof construction to form a substantially unitary coating for the roof construction; and then spraying a continuous stream of grit particles onto the coating. 55
3. The construction of a moisture-impervious roof construction from a roof construction having inherent moisture-pervious characteristics, in which the moisture-pervious roof construction has been located and assembled in position for use as such, which includes the steps of: forcing, under pressure, a continuous stream of liquid water-proofing compound to and spraying the compound onto the surface of the moisture-pervious roof construction to form a substantially unitary coating for the roof construction; and then depositing metallic particles upon the coating to form a substantially continuous metallic sheet for the layer. 60
4. The construction of a moisture-impervious roof construction from a roof construction having inherent moisture-pervious characteristics, in which the moisture-pervious roof construction has been located and assembled in position for use as such, which includes the steps of: forcing, under pressure, a continuous stream of liquid water-proofing compound to and spraying the compound onto the surface of the moisture-pervious roof construction to form a substantially unitary coating for the roof construction; and then atomizing metallic particles and driving them against the coating to unite them and form a substantially continuous metallic cover for the coating. 65
5. The construction of a moisture-impervious roof construction from a roof construction having inherent moisture-pervious characteristics in which the moisture-pervious roof construction has been located and assembled in position for use as such, which includes the steps of: forcing, under pressure, a continuous stream of liquid water-proofing compound to and spraying the compound onto the surface of the moisture-pervious roof construction to form a substantially unitary coating for the roof construction; and then, while the coating remains sufficiently plastic, spraying a continuous stream of grit particles at the coating under a sufficient pressure to cause the particles to become imbedded in the plastic coating. 70
6. The construction of a moisture-impervious roof construction from a roof construction having inherent moisture-pervious characteristics in which the moisture-pervious roof construction has been located and assembled in position for use as such, which includes the steps of: forcing, under pressure, a continuous stream of liquid water-proofing compound to and spraying the compound onto the surface of the moisture-pervious roof construction to form a substantially unitary coating for the roof construction; then, while the coating remains sufficiently plastic, spraying a continuous stream of grit particles at the coating under a sufficient pressure to cause the particles to become imbedded in the plastic coating; and thereafter atomizing metallic particles in a plastic state and driving them against the coating and the grit particles to unite the particles and form a substantially continuous metallic cover for coating and particles. 75
